UNITED STATES PATENT OFFICE.

HENRY CYR, OF BIDDEFORD, MAINE, ASSIGNOR TO DRAPER COMPANY,
OF HOPEDALE, MASSACHUSETTS, A CORPORATION OF MAINE.

HARNESS-MOTION FOR LOOMS.

No. 812,166.

Specification of Letters Patent.

Patented Feb. 6, 1906.

Application filed November 8, 1905. Serial No. 286,323.

To all whom it may concern:

Be it known that I, HENRY CYR, a citizen of the United States, and a resident of Biddeford, county of York, State of Maine, have 5 invented an Improvement in Harness-Motions for Looms, of which the following description, in connection with the accompanying drawings, is a specification, like figures on the drawings representing like parts.

This invention relates to harness-motions for looms, and it applies more especially to that type which forms the subject-matter of United States Patent to Roper, No. 770,116, dated September 13, 1904. In that patent 15 the heddle-frames are raised and lowered by mechanism including a system of rocking levers, coöperating cam-levers, and an actuator which is caused to actuate the several cam-levers in a predetermined order. Each 20 rocking or bent lever is in practice provided with two followers or rolls, one of which co-operates with the corresponding cam-lever to raise the heddle-frame, while the other acts in a similar manner to lower the frame. A 25 locking-rest on the cam-lever coöperates with one or the other follower to lock the heddle-frame in raised or lowered position until in the order or sequence of operation the position of the heddle-frame is to be changed. 30 When a heddle-frame is raised, the weight of the warp-threads governed thereby and their tension acts to maintain the proper follower in coöperation with the locking-rest of the corresponding cam-lever until the latter is 35 positively moved, and ordinarily the warp will act in a similar manner when the heddle-frame is in lowered position. In actual practice, however, when a very light warp is used it has been found that there is at times a 40 tendency to disengage the follower from the locking-rest when a heddle-frame is in lowered position or the coöperation of such parts is so slightly maintained that the cam-lever may be accidentally moved by the jarring of 45 the loom, and thereby get out of the proper timing, unlocking the heddle-frame. I have found that this is due to the fact that the light warp just about balances the weight of the heddles and a portion of the heddle-frame, so that the bent or rocking lever connected therewith is practically in equilibrium and the follower has so little tendency to remain in the locking-rest that the cam-lever can be jarred out of locking position,

whereupon the heddle-frame will not be held 55 locked.

My present invention has for its object the production of simple and effective means to act at the time a heddle-frame is lowered and maintain the locking means fully operative 60 and effective as long as required.

Figure 1 is a view in front elevation of a harness-motion of the type shown in the patent hereinbefore referred to with one embodiment of my invention applied thereto, 65 the heddle-frame being shown locked in its raised position; and Fig. 2 is a similar view of a portion of the mechanism shown in Fig. 1, but with the heddle-frame in its lowered position with the means operative for maintaining the locking means effective at such time. 70

It will be understood that as many heddle-frames will be employed as may be necessary; but I have herein shown only one of such frames for the sake of clearness. 75

As illustrated, the heddle-frame consists of a cross-bar 1 and two end bars 2 2, heddles 3 being supported on the cross-bar, such heddles in practice being longitudinally slotted to receive the cross-bar and having warp-eyes below the slots, as in said Patent No. 770,116. The end bars 2 slide in fixed vertical guideways 5, the upper ends of the bars being connected by links 6 and 7 to bent or rocking levers 8 and 9, pivotally mounted 80 upon the upper portion of the loom-frame, said levers 8 and 9 being connected by a link 10, oscillation of the lever 9 raising and lowering the heddle-frame, all as in the patent referred to. So, too, the arms 9' 9'', extending on opposite sides of the pivot of the rocking lever 9, and the followers or rolls 11 and 12, mounted on said arms to coöperate with the cam-surface of a cam-lever 13, are as in said patent, the depending coupler-bars 14 95 and 15, pivotally connected with the cam-lever, being caused, one at a time, to be engaged by a reciprocating actuator 17. The cam-lever 13 is also provided with a locking-rest 16, and by reference to Fig. 1 it will be 100 seen that when the heddle-frame is in its raised position the follower 12 coöperates with the locking-rest, locking the heddle-frame in such raised position. At such time the warp acts to pull down the links 6 and 7, 105 even if the warp is light, and thereby tends to press the follower firmly into the locking-rest. Referring to Fig. 2, however, it will be

seen that when the heddle-frame is in lowered position (with the follower 11 in coöperative relation with the locking-rest 16) there is no tendency to maintain such relation if the warp is light and practically balances the heddles and a portion of the frame—that is, the bent levers 8 and 9 are substantially in equilibrium—and the cam-lever 13 can be jarred out of locking position by the motion of the loom, so that the heddle-frame will be unlocked and the parts will be thrown out of proper timing.

In accordance with my invention in the embodiment thereof herein illustrated I fix an arm or bracket 20 to the loom side and attach thereto one end of a spring 21, the other end of the spring being attached to the rocking lever 9 above its pivot, one of such springs being connected with each lever 9 of the set. This spring is of such length that it will be inert or inactive when the heddle-frame is in its raised position, (see Fig. 1,) for at such time it would if permitted to act tend to disengage the follower 12 from the locking-rest. 16. When the heddle-frame is in lowered position, however, the spring is stretched (see Fig. 2) as the rocking lever 9 swings away from the bracket 20, and then the tension of the spring is exerted to pull said lever back again. This pull of the spring causes the then active follower 11 to be pressed firmly into the locking-rest 16, maintaining and insuring the coöperation of such parts so long as the heddle-frame is lowered and until the positive movement of the cam-lever 13 by the actuator 17 overcomes the action of the spring and disengages the follower 11 from the locking-rest. It will be obvious that if the rocking lever 9 be relieved of all weight whatever when the heddle-frame is down the spring will act to maintain such lever locked, and hence the means for locking the heddle-frame in its lowered position is maintained effective entirely irrespective of the character of the warp or its action upon the heddle-frame and connected parts at such time.

My invention may be varied or modified by those skilled in the art without departing from its spirit or scope, one practical and efficient embodiment of my invention being herein shown and described.

Having fully described my invention, what I claim as new, and desire to secure by Letters Patent, is—

1. A harness-motion for looms having, in combination, a heddle-frame, a rocking lever operatively connected therewith, a roll on said lever, a cam-lever to coöperate with said roll to depress the heddle-frame, said cam-lever having a locking-rest to engage the roll when the heddle-frame is in lowered position,

and independent means acting at such time through the rocking lever to maintain the roll in the locking-rest.

65

2. A harness-motion for looms having, in combination, a heddle-frame, a rocking member operatively connected therewith and provided with a follower, a cam-lever to coöperate with said follower to depress the heddle-frame, said cam-lever having a locking-rest to engage the follower when the heddle-frame is in lowered position, and means acting at such time to maintain the follower and locking-rest in coöperation, to prevent accidental movement of the cam-lever.

70

3. A harness-motion for looms having, in combination, a heddle-frame, a rocking member operatively connected therewith and provided with a follower, a cam-lever to coöperate with said follower to depress the heddle-frame, said cam-lever having a locking-rest to engage the follower when the heddle-frame is in lowered position, and a spring under tension at such time acting to maintain the follower and locking-rest in coöperation.

80

4. A harness-motion for looms, having in combination, a heddle-frame, a rocking member operatively connected therewith and provided with a follower, a cam-lever to coöperate with said follower to depress the heddle-frame, said cam-lever having a locking-rest to engage the follower when the heddle-frame is in lowered position, and a spring fixed at one end and connected at its other end with the rocking lever and stretched by movement thereof to lower the heddle-frame, the tension of the spring acting when the heddle-frame is in lowered position to press the follower into the locking-rest and thereby prevent disengagement and improper movement of the cam-lever.

90

5. A harness-motion for looms having, in combination, a heddle-frame, means to reciprocate it, including a cam-lever having a locking-rest, and a follower to engage the locking-rest when the heddle-frame is in lowered position, and means rendered operative at such time to maintain the follower in coöperation with the locking-rest.

100

6. A harness-motion for looms having, in combination, a heddle-frame, means to reciprocate it, means to lock the heddle-frame in raised or lowered position, and a safety device acting only when the heddle-frame is in lowered position to insure the operation of the locking means at such time.

115

In testimony whereof I have signed my name to this specification in the presence of two subscribing witnesses.
